UNITED STATES PATENT OFFICE.

FRANK KUHN, LAWRENCE H. THOMAS, AND JULES G. SPIESS, OF DETROIT, MICHIGAN,
ASSIGNORS TO AMERICAN ELECTRICAL HEATER COMPANY, OF DETROIT, MICHIGAN, A CORPORATION OF MICHIGAN.

HEATING UNIT FOR ELECTRICALLY-HEATED TOOLS.

1,407,692.

Specification of Letters Patent. Patented Feb. 28, 1922.

Application filed May 27, 1920. Serial No. 334,514.

To all whom it may concern:

Be it known that we, FRANK KUHN and LAWRENCE H. THOMAS, both citizens of the United States of America, and JULES G. SPIESS, a citizen of the Republic of France, having taken out first citizenship papers in the United States of America, all residing at Detroit, in the county of Wayne and State of Michigan, have invented certain new and useful Improvements in Heating Units for Electrically-Heated Tools, of which the following is a specification, reference being had therein to the accompanying drawings.

The invention relates to heating units for electrically heated tools of that type in which the terminals are carried outward through a hollow handle of the tool. It is the object of the invention to provide an armored heating unit which also protects the terminals, and to this end the invention consists in the construction as hereinafter set forth.

In the drawings:

Figure 1 is a perspective view of the unit; Figure 2 is an enlarged longitudinal section through the terminals, showing the protecting means therefor;

Figure 3 is a cross-section of Figure 2;

Figure 4 is a plan view of one of the armor plates.

The heating unit is of that type in which the resistor is wound or bent to extend in a zig-zag course about a flat core, said core and resistor being then enclosed by outer insulator plates and a metallic armor adjacent thereto. Reference is made to the patent to F. Kuhn and J. A. Hand 1,288,044 as showing the general arrangement of resistor upon a flat core. With such constructions it is usual to allow the terminals to pass outward from one end and in the incorporation of the unit into an electrically heated handled tool, it is necessary to thread these terminals through the hollow handle. The terminals are very delicate and easily injured, so that care must be exercised in the installing of the unit.

With the present construction the terminals, as well as the resistor, are armored and this armor is formed of tube segments respectively integral with the opposite armor plates for the flat unit. In detail, A is the unit having the armor plates B and C on opposite sides thereof clinched together

at their edges by the return-bends D. Each of these armor plates is provided with an outwardly extending shank E and these shanks are pressed to form the segment of a tube cooperating with the corresponding portion of the other plate to enclose the terminals. The terminals are formed by end portions of the resistor as indicated at F, which are held out of contact with each other by a series of cylindrical insulators G having separate longitudinal passages therethrough. These insulators will fit within the tubular shanks E and during assembly may be easily threaded upon the terminals and slipped within said tube.

With the construction as described, when the unit is mounted in the tool, the tube E can be readily inserted through the hollow handle, which will carry the ends of the terminals into position for connection with the external circuit.

What we claim as our invention is:

1. A heating unit comprising a flat insulated resistor, terminals leading therefrom, an armor comprising plates clamped upon opposite sides of said insulated resistor, and integral extensions of said plates forming segments of tubes for enclosing said terminals.

2. An electrical heating unit comprising a flat insulated resistor, terminals leading therefrom, an armor comprising flat plates arranged upon opposite sides of said insulated resistor, and integral extensions of said plates forming complementary segments of a tube for enclosing said terminals.

3. An electrical heating unit comprising a flat insulating resistor with terminals leading therefrom, a series of insulators sleeved upon said terminals to hold the same separate, and an armor comprising flat plates secured upon opposite sides of said insulated resistor, and extensions of said plates forming complementary segments of a tube for embracing said terminals and insulators thereon.

4. An electrical heating unit comprising a flat insulated resistor having terminals leading therefrom, insulators sleeved upon said terminals and holding the same from contact with each other, an armor comprising flat plates upon opposite sides of said insulated resistor and having their edges clinched together, and extensions of said

plates forming complementary segments of integral segmental extension for receiving tubes for embracing said terminals and insulators.

5. An electrical heating unit comprising
5 a flat insulated resistor with terminals leading therefrom, and an armor for inclosing said resistor having a flat portion and an

integral segmental extension for receiving said terminals.

In testimony whereof we affix our signatures.

FRANK KUHN.
LAWRENCE H. THOMAS.
JULES G. SPIESS.
